UNITED STATES PATENT OFFICE.

ASAPH WILDER, OF BYRON, CALIFORNIA.

SMOKE AND FUME CONDENSER.

1,162,325.

Specification of Letters Patent. Patented Nov. 30, 1915.

Application filed November 10, 1914. Serial No. 871,290.

To all whom it may concern:

Be it known that I, ASAPH WILDER, a citizen of the United States, residing at Byron, in the county of Contra Costa and State of California, have invented new and useful Improvements in Smoke and Fume Condensers, of which the following is a specification.

My invention relates to an apparatus which is especially designed to condense and reduce the smoke and fumes arising from combustion in furnaces so that the waste products of combustion may escape in the air without carrying with them large quantities of undesirable smoke and fumes.

The invention consists in the combination of a furnace, of draft and ejector attachments by which the direction of the products of combustion is insured, and in a series of agitating and condensing chambers, with connecting pipes, and an ultimate gasometer or receiver for such products as are not taken care of in the preliminary portion of the apparatus.

It also includes details of construction which will be more fully explained by reference to the accompanying drawings, in which—

Figure 1 is a general view in partial section of the apparatus. Fig. 2 is a sectional view of one of the condensing chambers.

As shown in the drawings, A is a furnace of any desired construction, B a boiler, C a breeching, and D a smoke stack connecting therewith and having within it a butterfly or other valve E by which a passage of the products of combustion through the stack may be arrested and said products turned into the cleansing portion of the apparatus.

2 is a pipe or passage connecting with the breeching and designed to conduct away the products of combustion therethrough when the valve E is so disposed as to close egress through the stack. Within this passage is a butterfly valve or other valve 3 which may be closed, when natural draft through the chimney takes place while the fire is being started; this valve being opened when the valve E is closed.

4 is a blast fan suitably arranged with relation to pipe 2 and having a connection directing the blast into said pipe in such a way that it acts as an ejector, forming a sufficiently strong draft through the furnace and breeching and driving the products of combustion onward through the pipe 2.

This pipe 2 is divided into two branches 2^a. By means of a valve 4^a the blast may be directed through either of the passages 2^a.

5—5 are tanks or receivers of any suitable size and each of the pipes 2^a connects with the bottom of one of the tanks. These tanks have within them horizontal diaphragms or partitions 6 at intervals; these partitions having passages or openings 7 made through them. Within each of the chambers thus formed is a fan or impeller 8 horizontally journaled and revoluble by means of pulleys 9 and connecting chains 10, power being derived from any suitable connection by which the fan 4 may also be driven.

From the upper part of the chamber 5 a pipe or passage 11 leads to a receiving or gas tank 12 suitably located with relation thereto. Escape passages or pipes 13 are connected with the lower part of the chambers 5 so that these chambers may be cleaned out at desired intervals. A steam pipe 14 with proper controlling valves, as at 15, is so connected that steam may be introduced either with or without the air blast, at will.

The operation of the device will then be as follows: When the fire is first made and the apparatus is cold, the damper E in the chimney D may be left open and a natural draft depended upon until the fire is sufficiently started. This valve is then closed and the valve or damper 3 in the pipe 2 is opened so that the products of combustion will be diverted into this pipe. At the same time the fan 4 being set in motion will form an ejector, driving the fumes through the pipe 2. The valve 4^a being turned to close one of the passages 2^a, the smoke, fumes and products of combustion will pass through this pipe and be delivered into the lower part of chamber 5. This chamber is filled with water, supply being brought thereto through the valve supply pipe 13. The smoke and products of combustion being forced into the lower part of the chamber and the fans 8 being in motion will thoroughly churn up and agitate the water and enable it to condense any of the lighter gaseous products, while the heavier carbon forming the smoke will be settled to the bottom; the lower chamber arresting most all these products and each of the upper chambers arresting successively a less portion while the gas will be discharged through the pipe 11 and into the tank 12.

Whenever it is desired to clean this tank,

it is only necessary to change the position of the valve 4^a and thus divert the smoke and fumes into the second tank 5, thus alternately operating so that the opportunity 5 is given to cleanse the tanks at intervals. The gas received in the gasometer 12 may be then drawn up or allowed to pass to any further apparatus by which such gas may be utilized, such apparatus not being here 10 shown.

Suitable pipe and hose connections are made with the tanks for the injection of water or cleansing substances whenever necessary.

15 It will be understood that the steam pipe 14 may be employed whenever desired either in conjunction with the agitator 4 or separately, if desired, and steam may also be conducted through suitable hose to assist in 20 cleansing the tanks.

Having thus described my invention, what I claim and desire to secure by Letters Patent is—

25 In an apparatus of the type set forth, in combination with a furnace, a water tank,

means to conduct the products of combustion from the furnace to the tank base, a series of horizontal and vertically spaced partitions in the tank forming top, bottom and intermediate chambers, each of said 30 partitions having an opening at one of its ends, the openings in adjacent partitions being in opposite sides of the tank, a horizontal shaft extending through the center of each chamber, an impeller on each shaft 35 located within the chamber and having horizontal blades arranged so as to sweep adjacent the sides, bottom and top of the respective chambers, said impeller blades having a sweep across points alined with and occurring both above and below the respective 40 openings, and means to drive the impellers.

In testimony whereof I have hereunto set my hand in the presence of two subscribing witnesses.

ASAPH WILDER.
